UNITED STATES PATENT OFFICE.

BENJAMIN B. SCHNEIDER, OF WILMETTE, ILLINOIS, ASSIGNOR TO STANDARD OIL COMPANY, OF WHITING, INDIANA, A CORPORATION OF INDIANA.

ART OF CONVERTING HYDROCARBON OILS.

Application filed June 12, 1925. Serial No. 36,596.

The present invention relates to improvements in the art of conversion of high boiling hydrocarbon oils into lower boiling point hydrocarbon oils such as gasoline or the like, 5 and will be fully understood from the following description, illustrated by the accompanying drawings, in which:

Figure 1 is a side elevation, showing diagrammatically apparatus for carrying the 10 invention into effect; and

Fig. 2 is a plan view of a diagrammatic layout of apparatus therefor.

Referring more particularly to the drawings, in Fig. 1, the numeral 5 indicates a 15 pipe still or heating coil to which oil is supplied under pressure through the line 6. In the pipe still 5 the oil is brought at least to conversion temperature of 720° F. or higher, and preferably to a temperature of 800 to 20 850° F. The oil is discharged from the pipe coil 5 before extensive conversion thereof has taken place, (e. g., not over 10%) the rate of flow being such as to prevent any substantial coke or carbon deposition within the 25 pipes. From the pipe coil 5 the heated oil passes through a line 7 into a chamber 8, preferably lagged or alternatively mildly heated to prevent substantial drop in temperature. In this chamber or tank the heated oil is retained at conversion temperatures 30 of 700 to 850° F. until a substantial further conversion into light products such as gasoline has taken place. From the chamber 8 vapors pass out through a vapor line 9 into 35 a dephlegmating tower 10 of any suitable type. Unconverted oil is withdrawn, preferably continuously, from chamber 8 through pipe 41.

Reflux formed in tower 10 is discharged 40 from the base of the tower to the line 11 and is forced by a surge pump 12 or other suitable device through a line 13 into the line 6 leading into the pipe still 5. The temperature of the vapors issuing from the tower 10 and the provision of reflux therein are controlled by the flow of oil through a closed coil 14 provided within the dephlegmator 10, in a manner more fully hereinafter set forth. From the dephlegmating tower 10, the 45 vapors of the desired low boiling products pass out through line 15 to a condenser 16, from which the condensate and cool vapors pass, preferably through a pressure reducing valve 17 into the receiver 18, which is

55 maintained at a superatmospheric pressure lower than that prevailing in the remainder of the system. From the receiver 18 the liquid product may be drawn off through the line 19 and vapors escape through the line 20 into a pressure gas line 21, which may 60 be connected with a low pressure gas line 22 by a suitable controllable release valve 23. A pressure of 4 atmospheres or higher, preferably 400 to 500 pounds is maintained 65 upon the system.

As will be apparent from Fig. 2, in operation, a plurality of units such as that shown in Fig. 1 are disposed in a battery. In Fig. 2, the various parts of each unit are designated by the same numerals employed in 70 Fig. 1, those appertaining to successive units being designated in addition by the subscripts "a", "b", "c", etc., respectively.

As will be noted from Fig. 2, the coil 14^a in the dephlegmating tower 10^a of the "a" 75 unit is supplied with oil through the line 25. The oil, in passing through the coil 14^a, exerts the desired cooling effect upon the vapors and is preheated. The preheated oil passes out through the line 26, which is 80 provided with a connection 27 leading to the line 6^b by which oil is forced into the pipe heater 5^b of the "b" unit. Similarly, the coil 14^b of dephlegmator 10^b of the "b" unit is supplied with oil through the line 28, 85 the preheated oil leaving the coil passing out through the line 29 which is provided with a connection 30 leading to the line 6^c by which oil is supplied to the pipe heater 5^c of the "c" unit. It will be noted that the 90 line 29 is also provided with a connection 31 by which oil may be supplied, if desired, from the line 29 to the line 6^a leading to the heater of the "a" unit. Flow of oil through the lines 30 and 31 is controlled by valves 95 30^a and 31^a respectively. Similarly, oil is supplied to the coil 14^c in the dephlegmator 10^c of the "c" unit through the line 32, and oil, heated in the coil 14^c passes therefrom through line 33 which is provided 100 with a connection 34 leading to the charging line of a later unit and also with a valve control connection 35 leading to the charging stock line 6^b of the "b" unit. It is to be noted also that the line 26 is connected 105 with a valve controlled connection 36 leading, in a similar way, to the charging stock line of a unit preceding the "a" unit (not

shown). Similarly, the charging stock line 6^a of the "a" unit may receive preheated oil from the coil in the dephlegmator of a preceding unit through the line 37. The lines 26, 29 and 33 are likewise provided with valve controlled connections 38^a, 38^b and 38^c leading to a manifold line 39 for preheated stock, this manifold line being connected with a lagged or insulated container 40. Connections 39^a, 39^b and 39^c are also provided between line 39 and charging stock lines 6^a, 6^b and 6^c of the respective units.

The operation may be described in connection with the "a" and "b" units of the battery or installation. In each unit, the supply of charging stock and the control of temperatures in the pipe heaters 5^a and 5^b respectively are independent. The necessary proportion of oil or charging stock is forced through the line 25 into the coil 14^a in the dephlegmator 10^a to produce the required cooling and refluxing action and to permit only the vapors of the desired product containing gasoline to leave the dephlegmator 10^a. The oil from the coil 14^a, and preheated therein, passes through the line 26 and the line 27 to become a part of the charging stock fed into the heater 5^b of the "b" unit. The proportion of oil thus fed into the "b" unit may, if less than the entire quantity of oil passing through the coil 14^a, be controlled by the valve in line 27, the remainder of the oil passing through the line 38^a into the manifold 39 and tank 40. If desired, the line 27 may be completely cut off and the oil coming from the coil 14^a be forced through the line 36 into a preceding unit, or the entire supply of oil may pass through the line 38^a into the manifold 39 and the tank 40, to be used as required in the various units to which the connections 39^a, 39^b and 39^c are provided. Similarly, the supply of oil to the line 28 through the coil 14^b in the dephlegmator 10^b of the "b" unit is independently controlled, and the oil from this coil passes through the line 29 either into the line 31 leading to the supply line 6^a of the "a" unit or through the line 30 into the supply line 6^c of the "c" unit. A connection 38^b is also provided between the line 29 and the manifold 39. The operation in this case may be the same as in connection with the preceding unit. A similar mode of operation is applied in connection with the subsequent units of the installation.

It will be readily apparent from the above description of the operation that there is a complete control of the cooling effect in each dephlegmator, and that this control is wholly independent of the requirements of oil of the unit which supplies vapors to the particular dephlegmator involved.

No claim is made in this application for the apparatus herein described, the same be-

ing claimed in my copending application Serial No. 36,597, filed June 12, 1925.

I claim:

1. The method of converting hydrocarbon oils into lower boiling hydrocarbon oils which comprises maintaining separate units, in each of which oil is passed through a heating coil in which it is brought to conversion temperature, the heated oil from said heating coil is forced into an enlarged chamber in which it is retained at conversion temperature until substantial conversion has taken place, residual converted liquid products are separately discharged from said chamber out of conversion conditions of temperature, and vapors from the conversion chamber pass to a dephlegmating zone, passing fresh oil through a closed conduit in the dephlegmating zone of one of said units, thereby producing a desired cooling and refluxing action therein, and discharging the oil from said closed conduit into the heating zone of another unit.

2. The method of converting hydrocarbon oils into lower boiling hydrocarbon oils which comprises maintaining separate units, in each of which oil is passed through a heating coil in which it is brought to conversion temperature, the heated oil from said heating coil is forced into an enlarged chamber in which it is retained at conversion temperature until substantial conversion has taken place, and vapors from the conversion chamber pass to a dephlegmating zone, passing fresh oil through a closed conduit in the dephlegmating zone of one of said units, thereby producing a desired cooling and refluxing action therein, discharging a desired proportion of oil from said conduit into the heating coil of another unit, and discharging the remainder into a reservoir.

3. The method of converting hydrocarbon oils into lower boiling hydrocarbon oils which comprises maintaining separate units, in each of which oil is passed through a heating coil in which it is brought to conversion temperature, the heated oil from said heating coil is forced into an enlarged chamber in which it is retained at conversion temperature until substantial conversion has taken place, and vapors from the conversion chamber pass to a dephlegmating zone, passing fresh oil through a closed conduit in the dephlegmating zone of one of said units, thereby producing a desired cooling and refluxing action therein, discharging a desired proportion of oil from said conduit into the heating coil of another unit, discharging the remainder into a reservoir, and feeding oil from said reservoir into the heating coils of selected units.

4. The method of converting hydrocarbon oils into lower boiling hydrocarbon oils which comprises maintaining separate units,

in each of which oil is passed through a heating coil in which it is brought to conversion temperature, the heated oil from said heating coil is forced into an enlarged chamber in which it is retained at conversion temperature until substantial conversion has taken place, and vapors from the conversion chamber pass to a dephleg-
mating zone, passing fresh oil through closed conduits in the dephlegmating zones of each of said units, and discharging oil from each of said conduits into the heating coil of a unit other than that in which the conduit is arranged.

BENJAMIN B. SCHNEIDER.
